Patented Apr. 4, 1916.

UNITED STATES PATENT OFFICE.

ALBERT BULLOCK, OF LOS ANGELES, CALIFORNIA.

PUMP.

1,177,989.

Specification of Letters Patent.

Patented Apr. 4, 1916.

Application filed June 16, 1913. Serial No. 773,808.

To all whom it may concern:

Be it known that I, ALBERT BULLOCK, a citizen of the United States, residing at Los Angeles, in the county of Los Angeles and

5 State of California, have invented certain new and useful Improvements in Pumps, of which the following is a specification.

This invention relates to improvements in pumps and especially to that class of pumps 10 which is provided with rotary pistons or impellers and it is an object of the invention to provide such a pump with impellers having vanes or blades arranged to take water or other liquids from an outside point and 15 discharge it at the center with a centripetal action.

It is also an object of the invention to provide a pump in which one or more impellers may be used having blades or vanes 20 curved transversely and set at such an angle that they will cut into liquids or materials at the outer periphery of the impeller and force the same inwardly so as to discharge from the center of the impeller.

25 It is a still further object of the invention to provide a pump in which a plurality of impellers may be employed having blades or vanes set to produce a centripetal action in the material pumped, the blades being arranged either parallel with the longitudinal axis of the pump, or inclined or spirally with respect thereto.

With these and other objects in view the invention comprises certain novel constructions, combinations and arrangements of parts to be hereinafter described and claimed.

In the accompanying drawing forming a part of the specification: Figure 1 is a 40 longitudinal view partly in section of a pump constructed in accordance with this invention. Fig. 2 is a transverse sectional view taken through the impellers of the pump and the intake opening, in a plane at 45 right angles to the plane of the section in Fig. 1. Fig. 3 is a detail perspective view showing a portion of one of the blades or vanes of the pump impeller, the cross sectional shape thereof being indicated in

50 section. Fig. 4 is a fragmentary sectional view through a pump casing showing a single impeller mounted therein. Fig. 5 is a detail view showing a pump in side elevation, mounted in a pit or well. Fig. 6 55 is a detail sectional view taken centrally

through a pump of a modified form of construction, and upon the line 6—6 of Fig. 7. Fig. 7 is a transverse sectional view taken upon the line 7—7 of Fig. 6:

The pump structure contemplated in the 60 present invention is designed to draw liquids or materials from the peripheral portion of the pump casing and force the same toward the center and through a central discharge opening, securing a centripetal or whirlpool 65 action.

In the drawing the preferred construction of the pump has been illustrated and the details and features of the invention will be specifically described. 70

In the drawing 10 indicates a casing, preferably inclosed at one end and provided with removable head or cover 11 at its other end. Mounted within the casing 10 is an impeller 12 having a hollow shaft 13 at one 75 end which passes outwardly through an opening in the head 11, a packing gland 14 being provided to afford a tight joint between the parts. The impeller 12 is formed with head portions at each end which are 80 connected by means of longitudinally extending vanes or blades 15. One end of the said impeller is closed by a plate 16 which is formed with a journal 17 adapted to extend into a journal bearing 18 formed in the casing 10. Ball bearings 19 interposed between the parts at the end of the journal 17 afford antifriction means for receiving the end thrust of the piston or impeller 12. The vanes or blades 15 may be arranged to 90 extend parallel with the axis of the impeller, suitable openings being arranged between them for permitting of an easy passage of the materials pumped.

The cross sectional shape of each of the 95 vanes or blades 15 is preferably approximately like that shown in Fig. 3, the outer edges of each vane being curved forward as at 20 so as to gradually and easily cut into the liquids or other materials pumped at the outer periphery of the impeller. The body portion of each blade is inclined toward the inner edge of the impeller and is curved as at 21 to slip easily from the said material at the inner edge of the blade. 100

Casing 10 is formed with an inlet opening 22 upon one side of the pump and the materials entering the pump pass therethrough and into a tapering diminishing space 23 within the casing, the walls of said casing 110

being of spiral formation in cross section as clearly shown in Fig. 2. The impeller 12 is so set in the said casing that it approaches closely the wall of the casing 10 at 23, to one side of the inlet 22. The impeller is rotated in the direction of the arrow 24 so that the blades move with the incoming stream and gradually cut into the same so as to force its substance toward the center. The shaft 13 may be provided with any rotating means as for instance a gear 25. It will be evident that a pulley or other force receiving means might be used to turn such shaft and the impeller 12.

15 The pump is preferably provided with a plurality of impellers and the vane carrying portion of the outer impeller 12 is made of sufficient size to afford ample space within to receive inner impellers. Thus as shown 20 in Figs. 1 and 2 an inner impeller 26 may be mounted within the outer impeller, said inner impeller having one head provided with a journal 27 engaging a bearing formed within the journal 17, and a ball or other bearing 28 may be interposed between the end of the journal 27 and the adjacent portion 25 of the casing 10 to receive the end thrust of the inner impeller. The other end of the impeller is provided with a hollow shaft extension 29 having a bearing within the shaft 13. A packing gland 30 between the parts prevents the escape of liquids or materials from the pump. The said shaft 29 is also provided with a gear wheel 31 by 30 which it may be rotated for driving the impeller. The inner impeller 26 is provided with vanes 32 preferably of similar shape in cross section through the vanes 15 of the outer impeller. The said vanes 32 are usually and preferably inclined or arranged in 35 somewhat spiral relation to the axis of the impeller as indicated in Figs. 1 and 2 of the drawing. The impeller 26 is driven in the same direction as the impeller 12 though 40 generally a little more rapidly thus preventing any back pressure of the materials pumped, the direction being indicated by arrow 33 in Fig. 2. The inner space or opening between the vanes 32 is usually as 45 large or of slightly larger diameter than the outlet opening or passage through the shaft 29. The materials delivered from the pump through said shaft 29 may be discharged in any desired manner or may be forced into 50 piping 34 having a packing gland 35 to surround and receive the rotating end of the said pipe 29.

A single impeller as shown in Fig. 4 may be employed instead of a plurality thereof 55 without departing from the spirit of the invention. Thus as shown in Fig. 4 the pump may have an impeller 36 made similar to the impeller 12 and when one impeller only is employed, the blades 37 thereof are preferably slightly inclined or spirally arranged,

though of course they can be kept in lines parallel with the axis of the impeller as in the case of the impeller 12 if preferred.

In operation, the inlet opening of the casing 10 is connected, usually by piping with the source of materials to be pumped. The impellers are then set in motion and where there are more than one impeller, the inner one is driven a little faster than the other ones. The liquids or other materials are thus drawn into the casing, the vanes of the impellers cutting into the stream and forcing said materials inwardly where they are again caught by the vanes of the inner impeller and forced outwardly from the center of the pump through the hollow shaft 29. The device may be connected in pipe lines of any kind for impelling or driving liquids therethrough or it may be set in vertical position as shown in Fig. 5 for lifting liquids or materials from a pit or well indicated at 38.

Other modifications of the invention may be adapted also to various uses within the scope of the invention. Thus as shown in Figs. 6 and 7 the impeller 40, may be provided with vanes 41 radiating from the central hub 42, the outer ends of the vanes being secured to the housing 43. The vanes which are preferably about the same in cross sectional shape as those heretofore described, thus leave inclined openings between them as shown in Fig. 6. The radial arrangement and tapered formation of these vanes will also be apparent by reference to Fig. 7. The housing of the impeller is preferably somewhat larger than the hollow driving shaft of the device. The hub 42 has a projecting bearing end portion adapted to be seated and held against end thrust by a spider 45 mounted in said housing 43. The arms 46 of the spider may be inclined and shaped as shown in Fig. 6 to give direction to the liquids pumped and tend to whirl or rotate the same so that the vanes of the impeller will readily cut into and force the same through the outlet shaft 44. Such an impelling pump is well adapted for interposition in pipe lines for impelling liquids such as oil and the like, as well as for lifting liquids. It will be understood that when the impellers of the forms described are driven at proper speed, the liquids or materials pumped will be given a twisting movement and will be forced along with somewhat a whirlpool action at the outlet.

What is claimed is:

1. A pump having a peripheral inlet and a central outlet and impellers having vanes with flat body portions and forwardly curved material cutting edges adapted to move materials with a centripetal action.
2. A pump comprising a casing having a lateral inlet, a rotary piston mounted there-

in and having a central outlet, said piston having blades forwardly curved at their entrance edges and reversely curved at their other edges and means for rotating the impeller to drive materials through said central outlet.

3. A pump having outer and inner impellers, the outer impeller having vanes parallel with the axis thereof and the inner impeller having vanes set in twisted relation to the axis of said impeller and means for rotating the said impellers.

4. A pump comprising a casing having a peripheral inlet, an impeller mounted there-in and having a hollow shaft projecting through the wall thereof whereby it may be turned, said impeller having vanes extending longitudinally of the impeller and having curved outer edges adapted to cut into the materials to be pumped, and an inner impeller having a hollow shaft projecting through the shaft of the outer impeller for delivering the materials pumped, said inner impeller having vanes arranged upon a spiral twist and formed with outer cutting edges adapted to force the materials pumped through the said hollow shafting, and means connected with each of the hollow shafts for turning them and driving the impellers.

5. A pump having a casing formed with 30 antifriction bearings at one end and a discharge outlet at the other end, said casing also having an inlet opening in its side wall, impellers mounted within the said casing and having concentric journals engaging 35 said antifriction bearings, said impellers also having concentric hollow shafts adapted to conduct the materials pumped through the outlet opening of the casing.

6. A pump comprising a casing having a 40 lateral intake and an axial outlet, an impeller mounted in said casing having heads and connecting vanes arranged with spaces between them, said vanes having their inner edges curved forwardly in the direction of 45 the movement of the impeller, and their outer edges tapered and curved in the other direction, the structure being such that upon rotating the impeller materials will be drawn inwardly and forced through the 50 said axial outlet, and means for rotating the said impeller.

In testimony whereof, I have hereunto set my hand, in presence of two witnesses.

ALBERT BULLOCK.

Witnesses:

LILLIE VOLLMER,
CASSELL SEVERANCE.
